UNITED STATES PATENT OFFICE.

PAUL W. ROKOHL, OF NEW CANAAN, CONNECTICUT.

RAILROAD-TIE.

1,257,123.

Specification of Letters Patent. Patented Feb. 19, 1918.

Application filed August 8, 1917. Serial No. 185,135.

To all whom it may concern:

Be it known that I, PAUL W. ROKOHL, a citizen of the United States, residing at New Canaan, in the county of Fairfield and State of Connecticut, have invented certain new and useful Improvements in Railroad-Ties, of which the following is a specification.

This invention relates to railway ties, and more particularly to metallic ties of hollow construction.

One of the main objects of the invention is to provide a tie of the character stated of simple construction which may be produced at relatively small cost.

A further object is to provide a tie having a slot to receive securing bolts for fastening the plates for holding the rails in position on the tie, this tie being further provided with a reinforcing member communicating with the slot and adapted to support the securing bolt and hold the same against rotation. Further objects will appear from the detailed description.

In the drawings:

Figure 1 is a top view of a tie constructed in accordance with the invention as applied.

Fig. 2 is a longitudinal central vertical section taken through the tie as applied.

Fig. 3 is an end view of the tie.

Fig. 4 is a similar view of a modified form.

The tie 1 is of substantially rectangular cross section having the side walls 2 and 3, bottom wall 4, and top wall 5. This tie may be cast of any suitable material though I prefer to employ malleable iron casting. A slot 6 is provided at the center of the top wall 5 and extends the full length of the tie. This slot communicates directly with the interior of a depending substantially U-shaped member 7 formed integral with the top wall. This channel member is adapted to slidably receive the square head 8 of a securing bolt 9 inserted into the same with its shank or stem projecting through slot 6. The channel member serves, in this manner, to secure the bolt against rotation and also to support it in proper position with the shank portion thereof projecting through the slot 6.

The tie is provided, adjacent each end, with two spaced oppositely directed series 10 and 11 of serrations or teeth. The series 10 of serrations is adapted to engage a co-operating series of serrations formed on the under face of a securing plate 12 which is secured on the tie by the spaced bolts 9

inserted through suitable apertures through the plate, the usual securing nut being threaded on each bolt above the plate. A plate 15 similar to plate 12 is provided on its under face with a series of serrations which co-operate with the series 11 formed on the tie, this plate being secured in position by the bolts 9, the two plates co-operating to secure the rail 18 on the tie.

The securing bolts, when first placing the tie in position, may be readily inserted into the channel member 7 from each end of the tie. To permit insertion of bolts after the rails have been secured to the ties, I provide aligned rectangular recesses 19 and 20 at the longitudinal center of the tie communicating with the slot 6. These recesses are of sufficient size to permit ready insertion of a bolt head into the channel member 7, the bolts being freely movable toward either end of the tie after being thus inserted into the channel member.

In the modified form shown in Fig. 4, the under or bottom wall 4 of the tie is provided with a central longitudinally extending slot 6^a corresponding to slot 6 of the top wall of the tie. This slot 6^a communicates directly with the interior of an upwardly extending channel member 21 formed integrally with bottom wall 4 corresponding to channel member 7. Channel member 21 and slot 6^a co-operate to receive the heads and shanks of suitable securing bolts inserted into the same so as to retain these bolts and prevent rotation thereof. This form of tie is especially adapted for use in connection with bridges, elevated railways, and similar structure; the channel member 21 and slot 6^a providing means whereby the tie may be quickly and easily secured to a structure of this character.

A tie constructed in this manner, in addition to being very strong and relatively light, may be produced at relatively small cost and is well able to withstand the vibration to which it is necessarily subjected. To prevent distortion or lateral spreading of the tie under unusual loads or strains, suitable tie bolts 22 may be inserted through the side walls 2 and 3, these bolts being secured in position by nuts 23 threaded on to the same.

While this tie has been shown and described as used with rail securing plates of a specific form, it will be understood that it may be equally well used in connection

with securing members of various types, and I do not desire to in any way limit myself to the particular type of securing plate illustrated. It will be equally evident that the tie can be of any length desired so as to be used for switches, crossings, and other purposes.

What I claim is:

A hollow tie of substantially rectangular cross section provided in its top and bottom wall with longitudinally extending slots, said slots extending the full length of the tie, said tie having an integral depending reinforcing channel member of rec-

tangular cross section carried by the upper 15 wall thereof and communicating directly with the slot through said upper wall, and an upwardly extending channel member of rectangular cross section formed integral with the bottom wall of the tie and communicating directly with the slot through 20 said bottom wall.

In testimony whereof I affix my signature in presence of two witnesses.

PAUL W. ROKOHL.
